ABSTRACT

A high-speed photographic type-composing machine is disclosed. Light is projected from a source of illumination such as a cathode-ray tube, laser, or multiplicity of flashlamps through a plurality of light-directing means such as light channels to an arcuate projection zone which is formed by a portion of the curved surface of a rotatable character-carrier. The light channels may be movable in unison among a plurality of discrete positions relative to the arcuate projection zone. The characters are carried on filmstrips which are mounted on a rotatable drum by rigid holding means in the form of arcuate segments, and the characters continually pass through the projection zone, which is large enough to include a plurality of characters at any given time. Selected characters are projected from the zone to an image-receiving surface (such as a film) by an optical projection system which may include a field-flattening lens. Control circuitry is provided for storing and sorting selected characters such that these characters may be illuminated in a sequence which is dissimilar to their respective positions in the composed line. The control circuitry is adapted to achieve this result by varying the time at which any selected character is illuminated as it passes through the projection zone, and is further adapted to center lines on the film by delaying the projection of the first character of the line by a time interval which is dependent upon the selected point size. Also, the film may be incrementally moved by stepping motors in order to compensate for relative displacement between the film and characters if the character-type style and/or point size is changed.

PHOTOGRAPHIC TYPE-COMPOSING MACHINE

BACKGROUND AND BRIEF DESCRIPTION OF THE INVENTION

This invention relates to a photographic type-composing machine, and is a continuation-in-part of copending U.S. application Ser. No. 629,300, filed Apr. 7, 1967 now abandoned, which is in turn a continuation-in-part of Ser. No. 368,839 now U.S. Pat. No. 3,291,015, of Ser. No. 441,738 now U.S. Pat. No. 3,422,736, of Ser. No. 506,936 now U.S. Pat. No. 3,416,420 and of Ser. No. 617,912 filed Feb. 23, 1967 now 3,512,562. The foregoing cases are expressly incorporated by reference into the present disclosure.

At present, there is an increasing demand for photographic type-composing machines which are computer-compatible; that is, for a phototypesetter which is able to handle the rapid output rate of a high-speed computer. Previous phototypesetters such as the Photon ZIP machine described in U.S. Pat. No. 3,273,475 have attained speeds which are suitable for the composition of computer printout. Unfortunately, speed of composition is not the only parameter which must be satisfied in a machine of this nature. Versatility is also quite important—a desirable machine must be capable of providing a reasonable variety of character type styles and point sizes. Moreover, the positional accuracy and typographical quality of the composition must reach an acceptable level.

The present invention fully satisfies all of the above-mentioned parameters. A rotatable character-carrier such as a continuously revolving drum carries a plurality of flexible filmstrips mounted to the curved surface of the drum by rigid arcuate segments. Each filmstrip includes a plurality of spaced master characters, such that there are 918 character positions in one embodiment of the invention. An arcuate projection area or zone is formed by a portion of the curved surface of the character drum. The character filmstrips are arranged in coaxial rings of various character type styles which pass simultaneously through the projection zone. A lens turret in the optical projection path provides a point size changing capability. Thus, the foregoing arrangement fully satisfies the versatility requirements dealing with type style and point size.

Moreover, the arcuate projection zone is sufficiently large to include a plurality of characters at any given time as the character filmstrips endlessly pass through the projection zone. Since the zone is arcuate, the optical projection system includes optical means, such as a field-flattening lens, adapted to project the arcuate zone onto the film as if the zone were flat, thus producing an undistorted image of the zone. The source of illumination for the characters may be a cathode-ray tube (CRT), a laser having associated beam-deflecting crystals, or a multiplicity of flashlamps. No matter which illuminating means is utilized, each source must be capable of illuminating a plurality of discrete positions within the arcuate projection zone. To assist in the attainment of this objective, light-directing means may be positioned between the light source and the arcuate projection zone. The light-directing means may comprise a plurality of light channels such as fiber optics pipes or rods, or an optical fiber screen, or may consist of mirrors, prisms or other equivalent optical light-directing means. When light channels are used, they may, if desirable, be movable in unison to a plurality of discrete positions relative to said arcuate zone.

In addition, control means are provided to vary the time at which the illuminating means is energized so that a selected character may be illuminated at any given time as it passes through the projection zone. Thus, the projected images of the characters comprising a line of composition may be spaced from one another along a common baseline of the film according to their respective widths. The control means further include means for storing a complete line of characters which are to be composed, prior to projecting the first character of the line, and means for sorting each of the stored characters in accordance with: (1) its respective location on the drum relative to a predetermined reference point, (2) the accumulated

widths of the preceding characters in the line to be composed (assuming a right-reading line). Using this arrangement, the characters may be illuminated in a sequence which is dissimilar to their position in the composed line, thereby allowing a full line to be composed for each revolution of the character-carrier. Only when the characters are flashed in their physical order on the matrix strip will the composed sequence be the same as the flash sequence.

It is understood, of course, that if a wrong-reading (i.e., right-to-left) line is to be composed, sorting will be based upon the accumulated widths of the "succeeding" (rather than "preceding") characters in the line to be composed. Likewise, the character matrix may, if desired, be a revolving sphere, or a continuously moving band as depicted in U.S. Pat. No. 3,416,420—in other words, any arrangement in which the characters repeatedly pass through a projection zone or area at ascertainable intervals. It is also apparent that a relatively large projection zone which includes a plurality of characters at any given time could be replaced by more than one "subzone" each embracing a single character at any time. In either case the characters must be projected to a common baseline on the film. Thus, if the subzone concept is employed the optical projection system would be modified as required; for example, by including an optical merging system or the like so that the film "sees" the same image as that of the relatively large projection zone.

Therefore, composing speed is significantly increased by providing a projection zone large enough to include a plurality of characters, and—after sorting the characters in such a manner that a full line of characters may be projected for each revolution of the character-carrier—means for illuminating each selected character at any time during its passage through the projection zone, in order to project a line of composition having characters spaced from one another according to their respective widths.

Because of distortions which may occur if characters are projected when located at the extreme ends of the arcuate projection zone, together with the fact that the maximum length of line of a given "rectified" arcuate projection zone is dependent upon the selected point size, circuitry is provided for centering the line to be composed on the axis of the optical projection system. This is accomplished by delaying the projection of the first character of the line to be composed by a time interval which is dependent upon the selected point size.

In virtually every instance where the type style or point size is changed, a compensating correction must be made if a common baseline is to be maintained. In the present invention, the film is moved by a leading mechanism (comprising separate fine and coarse stepping motors and a differential) in order to compensate for relative displacement which occurs between the film and the characters being projected when the style or point size is changed.

Thus, the aforementioned third parameter of positional accuracy and typographical quality is satisfied by providing electronic line-centering and style/size change compensation means. It is apparent therefore, that the present invention constitutes a machine which will satisfy the requirements of a user as to speed, versatility and quality of composition.

The invention will be more fully disclosed in the detailed description which follows, in which:

FIG. 28 is a schematic representation of the three positions of the movable light pipes in one embodiment of the invention;

FIG. 29 depicts a sample line of composition, above which are shown the three positions of the movable light pipes;

FIG. 30 is a table showing the rank value of each of the matrix characters relative to a predetermined reference point;

FIG. 31 is a comprehensive table showing the width, accumulated widths of previous characters, bundle position, flash unit number, rank value, flash value, and retained flash value of each character in the sample line of composition;

FIG. 32 is a table showing the flash channels which will illuminate the characters, based upon the accumulated widths of the preceding characters in the line of composition;

FIG. 33 is a table depicting the flash sequence of the characters;

FIG. 34 is a partial cross-sectional view similar to FIG. 21, but with fixed light-directing means;

FIG. 35 is a plan view of FIG. 34, showing the flashlamps, fixed light pipes and related equipment;

FIG. 36 depicts a sample line of composition for the fixed light pipe embodiment of FIG. 35;

FIG. 37 is a front view of the fixed light pipes of FIG. 35;

FIG. 38 is a plan view of FIG. 37, including a lenticular diffusing material to ensure uniform light distribution in overlapping areas of adjacent light pipes;

FIG. 39 is a table depicting the flash channels in a manner similar to FIG. 32;

FIG. 40 is a table showing the flash sequence of the sample of composition set forth in FIG. 36;

FIG. 41 is a schematic representation similar to that of FIG. 28, except that the light pipes are movable between two, rather than three, discrete positions;

FIG. 42 depicts a position of a character matrix showing equal spacing between adjacent characters, but unequal spacing from one character reference line to the next;

FIG. 43 is a partial cross-sectional view of a machine in which the illuminating means comprise a pair of lasers;

FIG. 44 is a plan view of the fixed light pipes of FIG. 43; and FIG. 45 is a view of the ends of the light pipes which are adjacent to the deflection crystals as seen in FIG. 43.

15 DETAILED DESCRIPTION OF THE INVENTION

The machine schematically represented in FIG. 1 incorporates features described and claimed in our aforementioned patents and copending application. In the embodiment shown, 20 the character matrix is in the form of a continuously rotating drum 20 pinned to a shaft 22, continuously driven by motor 24 mounted on the general frame of the machine 26. The drum 20 can be of the general structure described in U.S. Pat. No. 3,422,736 and incorporated in commercially available 25 machines known as Photon 713 Textmaster. As mentioned previously, the matrix may also be a continuously moving character-carrier such as a sphere or a band like that shown in U.S. Pat. No. 3,416,420. Drum 20 is provided with apertures 28 through which character images are projected. The characters, preferably transparent on opaque background, are carried by matrix strips or segments 30. There are preferably several rows or levels of master characters, generally of different typeface or design shown at 32, 38 and 42 on the surface of the drum. As they continuously move in the same path, 30 characters are projected on to a photosensitive surface 66 by illuminating means capable of producing flashes of very short duration.

In the example of FIG. 1 the selected characters are illuminated by a cathode-ray tube 46 provided with a fiber optics 40 faceplate 48. The illuminating source is preferably located outside the continuously rotating drum and the light beams emanating from the illuminated characters are deflected by a mirror 52 attached to a holder 54 secured to member 56 attached to the general frame of the machine 26. The image-carrying light beam, after deflection by mirror 52, enters a lens system 58 which may be one of several systems of varied focal lengths attached to a lens turret 60. The light emerging from lens system 58 makes an image of selected characters on photographic film 66 contained in a magazine including a light 50 impervious enclosure partially shown at 68. After the projection of each line the film is moved lengthwise in the direction indicated by arrow 74, for leading or line-spacing purposes.

The preferred film-handling system used in the machine is such that between supply spool 72 and takeup spool 98, the film makes two loops 78 and 95 controlled by film-sensing means 80, 82 and 94, 96 respectively, which can take the form of spring-loaded plungers that actuate switches to either stop or start film-feeding operations, as is well known in the art.

60 The film is continuously kept under tension by the combined action of rollers 84, which are continuously urged by a torque motor 85 in the opposite direction to the normal line-spacing direction, and by the driving system comprising drive roller 88 and satellite rollers 90. The satellite rollers 90 can be driven 65 through gears (not shown) in order to exert a considerable pull on the film each time the film feed mechanism drives the roller 88. A vacuum base 86 may be used to keep the film flat and in the focal plane.

A glass plate 104, attached to the base of the drum is provided with slits or marks 106 and 108 (FIG. 2) to generate timing and control pulses. There are produced by photodiode 116 receiving light from lamp 112 and optical system 114. The optical system 114 projects a luminous slit of generally narrow width to the plane of disc 104 on which the timing marks have 75 been produced by photographic means or otherwise.

The optical system 58 is designed to project on a film plane 66 in FIG. 7 a practically undistorted image 33' of a curved section of the area of the matrix drum, which will be termed an "arcuate projection zone," comprised within a certain angle 120, and of relatively narrow width. In other words, the optical system sees the curved area 33 as though it were a flat area of the same length and width as shown in dotted lines at 12. In order to accomplish this, a field-flattening lens may be used, or any equivalent optical means for projecting the arcuate zone as if it were flat.

In the embodiment described, the character selection and flash-timing system operates basically as described in U.S. Pat. No. 3,273,475 which is hereby incorporated by reference. It will be noted that in FIGS. 3 and 4 the characters in projection position are located on a curved-matrix cylindrical band 30. The characters of the matrix drum can be illuminated for a very short time by a cathode-ray tube 46 (also referred to as CRT) placed adjacent to the matrix drum (FIG. 1). The CRT causes a patch of light shown at 118 to illuminate an area containing a selected character at the appropriate time, as said character is moving within angle 120. This angle is defined as the projection angle or "arcuate projection zone" and it includes that portion of the surface of the drum which is flattened or "rectified" by lens system 58. This angle is represented on the matrix plane by two imaginary limit lines 122 and 124 separated by a distance T. One of these lines represents the first position at which the first character of a line can be projected and the other line the last position at which any character may be projected.

To facilitate the understanding of the operation of the machine the curved-matrix segment is shown in its rectified form as though the master characters were carried by a continuously moving strip 126 as explained in detail in U.S. Pat. Nos. 3,291,015 and 3,416,420. Master characters are separated by a distance "d" expressed in selected "units," for example in fractions of an em. In the example shown it is assumed that the matrix is provided with 6-point characters and the selected basic unit is one-eighteenth of a 6-point em. These characters are also all aligned on the same baseline 128. As the matrix moves continuously past the lens system 58 in the direction of arrow 6 potential images of the matrix characters continuously cross the width of the film 66 in the direction of the arrow 130 (as explained in U.S. Pat. No. 3,273,475) as they pass within the area of angle 120. In FIG. 3 the limit lines 122 and 124 represent the extreme boundaries of the rectified drum surface and are projected at PP and OO respectively on the film plane. The distance J comprised between lines PP and OO represents the maximum length of line that can be obtained in the example illustrated.

As the drum rotates the potential images of all of the characters of the matrix successively cut the line OO representing, for example, the left-hand margin of the composed text. During one revolution (or a fraction of a revolution) of the matrix drum the system operates as though an alphabet of potential images were moved from position x to position y along a common baseline 128 and in the direction of arrow 130.

The illumination of a preselected character of the line to be composed is obtained by instantaneously deflecting the beam of a CRT, and creating a light patch on the face of the CRT of an effective duration of the order of 2 microseconds. It can be said, for purpose of illustration that the CRT is suddenly instructed by the control means or computer section of the machine to direct its beam to the instantaneous location of a fast-moving character of the adjacent matrix and flash the image of this character at the time the matrix drum has reached an exactly predetermined position during its continuous rotation. The "home" position of the CRT beam from which it is moved to "hunt" for the selected character is such that if a luminous patch were produced at this position it would be at position 118', adjacent to the limit line 124, as shown in FIG. 3.

The distance "d" separating two consecutive characters of the matrix has been made relatively large in order to decrease

the accuracy required of the CRT deflection circuit. Through the use of an appropriate "extruded" electron beam the tube can produce on its face an approximately square luminous patch. In this embodiment this area is purposely made substantially larger than the maximum area which can be occupied by a character so that the CRT beam can be located with a tolerance as high as plus or minus one thirty-second of an inch. Of course the CRT end plate (which is not shown in FIG. 3) is preferably located close to the matrix band. In the present invention the character to be projected is caught "on the fly" at a location in the arcuate projection zone which is continuously variable so that there is not a given location on the face of the CRT assigned to a given character.

In order to accurately time the moment at which the CRT must be unblanked to produce a flash and also in order to cause the exact deflection of the beam, the matrix 30 may be provided with at least one row of timing slits 132 which, when read by a photoelectric reading arrangement, cause a pulse to be generated each time the matrix has moved the equivalent of one-eighteenth of an em. It is a matter of choice whether the slits are located on the matrix as shown in FIG. 3 or on a disc 104 as shown in FIGS. 1 and 2.

The characters of a line will be projected in an order determined by their location in the matrix and the accumulated width of preceding (or following) characters as fully explained in U.S. Pat. No. 3,273,475. The control means or computer section of the machine includes means for storing a complete line of characters to be composed, prior to projecting the first character of the line, and means for sorting each of the characters of the stored line in accordance with its respective location on said character-carrier relative to a predetermined reference point, and with the accumulated widths of the preceding (or "succeeding") characters in the line to be composed, so that the characters may be illuminated in a sequence which is dissimilar to their position in the composed line. This enables a full line to be composed during each revolution of the character-carrier.

For purposes of illustration only in this particular embodiment, the master characters of the matrix are equally spaced by a distance "d" equal to 30 units. As explained in U.S. Pat. No. 3,273,475, the distance "x" in units from the left hand reference line (such as "b-b," FIG. 4) of a given potential character image to an imaginary line a-a located at 30 units to the right (direction of travel) of the reference line of the first character of the sequence is equal to 30 times the "rank value." As the projection of the alphabet moves from position 1 to position 2 there will be a time at which the line a-a, located at 30 width units from the reference line of the first character of the alphabet in the "sweep" direction, will coincide with the line O-O, the latter line representing the left-hand margin of the line to be composed. The matrix 30 may carry timing slit 132 which activates an appropriate circuit effective to generate timing pulses as soon as the line a-a coincides with the line O-O and thereafter one impulse is generated each time the alphabet image moves a unit distance equal to one-eighteenth of an em. This unit value is used for all measurements of line and character widths in the present description, unless otherwise specified.

As the left-hand reference line b-b (FIG. 4) of the first character "A" of the alphabet is situated at a distance from the line a-a equal to 30 units, it is clear that when the line a-a has moved 30 units to the right of the line O-O, the character A is in position to be projected flush with the left-hand margin of the text, represented by the line O-O. As another example, the fifth character of the sequence, character "E," will be in position for projection at the same location, flush with the left-hand margin, 150 pulses after the line a-a has crossed the line O-O.

The location of the characters in the line does not, of course, depend solely on the location of the characters in the alphabet but also on the space occupied by all the preceding characters in the selected line, including justifying spaces. Consequently, it is necessary in order to determine the mo-

ment at which any character is to be projected on to the film, to add to its rank value, expressed in units, a value also expressed in units equal to the sum of the widths of the individual characters and spaces preceding that character including justifying space values, if any. The sum of these values is called the "displacement value" or "flash value" in the present description. The beginning of the passage of an alphabet or any preselected group of characters is identified by a pulse generated by a photocell cooperating with illuminating means and a mark 133 (FIG. 3). This pulse occurs at the moment the reference line $a-a$ of the first character of the sequence "A" cuts the line O—O representing the left-hand margin of the line. Following this initiating pulse, fine timing pulses are continuously generated by marks 132, which can be located either on a separate disc as shown in FIG. 2 or on the matrix itself as shown in FIG. 3. These timing pulses are counted from the moment the initiating pulse occurs. They are utilized to represent the actual position at any given instant of any character of the matrix and consequently its conjugate potential image on the film.

As explained in U.S. Pat. No. 3,416,420 the accumulated width of all the characters preceding, in the line, the character next to be projected (and generally including this character) controls the horizontal deflection of the CRT and the displacement value or "flash value" controls the instant at which the light must appear at the back of the character to be projected, represented by the number of pulses counted from the initiating pulse.

In the arrangement shown schematically in FIG. 8 the faceplate of CRT 46 is a conventional glass faceplate. A lenticular plate or film 140 is positioned at the proper distance from said faceplate to produce rays of collimated light 142. A lens 144 which may be of a "Fresnel" type is located close to the plate 140, in order to project at its focal point located in the entrance pupil of the optical system 58 an image of the light source represented, in this case, by the faceplate of CRT 46 thereby causing optimum illumination of the selected character on matrix 30. In other words, lens 144 is adapted to focus light emerging from collimating lens 140 to a focal point of the optical projection system.

In the alternative arrangement of FIG. 9 the CRT faceplate is shown at 146. It is made of optical fibers radially arranged in relation to the effective center of deflection 148 of CRT 46. The faceplate terminates as close as possible to the matrix 30, and at this terminus bundles of optical fibers are directed toward the optical system of the machine in order to project as much light as possible to the entrance of said optical system. The fibers are positioned such that their "matrix" ends terminate at locations which are equidistant from the arcuate projection zone of the matrix.

It is generally desirable in a photographic type-composing machine to have many characters of different styles available with as short access time as possible. In the arrangement which will now be described the matrix drum is provided with three rows of characters located at different levels along the vertical axis of the drum. These rows are shown at 32, 38 and 42 in FIG. 1 and FIG. 5. The machine generally produces a full line of text for each passage of a complete "alphabet" including generally uppercase and lowercase characters. It is desirable to move the film up for line-spacing purposes in as short a time as practicable so that a fresh area of the film is in position to receive the next line of text at the time the first character of the alphabet in use crosses again the first boundary line of the rectified arc. It has been found that one of the best arrangements is to have several complete "alphabets" of different styles around the periphery of the drum for each row of characters. In the arrangement now described three groups of 102 different characters representing an "alphabet" along each character row are provided. In one of the embodiments of the invention the angle 120 is equal to 40°. The complete passage of an alphabet in the projection area requires a rotation of 120° (representing the space occupied by the alphabet) plus 40°. This leaves 200° of drum displacement for line-spac-

ing (or leading) purposes. As the drum may rotate at the speed of 10 revolutions per second, or 1 revolution every 100 milliseconds, to produce 10 lines per second, the time available to move the film up is approximately 55 milliseconds. This value has been found to be sufficient for the spacing of ordinary lines of text.

The matrix characters may be carried by curved holding means comprising rigid arcuate segments as shown in FIGS. 5 and 6. In these figures the matrix characters are located on a filmstrip 150 sandwiched between a stainless steel frame 152 provided with apertures 154 and two longitudinal cover strips 156 and 158, attached to frame 152 by small rivets or other suitable fasteners—if desired, a single longitudinal cover strip may be used in lieu of strips 156 and 158. Each row of characters of different styles 32, 38 and 42 is provided with 34 characters, 17 in each aperture 154. Bearing surfaces 160 of the matrix segment are accurately machined to fit into a groove of the matrix drum.

The general control circuit of the machine will now be described in relation with FIG. 10. The machine can be controlled by either magnetic or paper tape or other kinds of inputs. Although it is desirable in certain cases to control the machine from a tape bearing no other information than the codes necessary for character identification as well as certain function signals, as described in U.S. Pat. No. 3,273,475, the present description will assume that the tape introduced into reader 170 of the machine has been processed in a computer in order to justify each line by introducing the required amount of spacing between words and characters. It must be clear at this point that this is not a limitation and that the control circuit of the machine can be expanded to justify and even hyphenate so-called "idiot" tapes. Part of the operations which will now be described could also be performed by a general purpose computer. The machine could be operated "on line" or "off line" with an appropriate computer.

The first element shown in the block diagram of FIG. 10 is a tape reader 170 which preferably reads at least one full line of text at a time. The identification codes are transferred via wire 171 to a buffer decoder 172 which discriminates function codes from character codes. The function codes are transferred over wire 174 to a section 191 of memory 194. Function codes corresponding to certain style shifts, as they are decoded, direct character code pulses via wires 174 and 175 to one of three sections of rank table memory block 176. Each of the three sections corresponds to a different 102-character alphabet of a row of the matrix and to one of two subdivisions of each section corresponding to uppercase and lowercase characters. The "rank value" thus obtained by the common action of a character identity code and a style shift code representing a given one-third of the circumference of the drum in the stored tables will now identify the location of this character in relation to the first character of a complete sequence or the initiating mark 108 (that is, a predetermined reference point) of FIG. 2 indicating the end of a drum revolution and the beginning of a new one. A style shift code also causes the selection of one of nine sections of memory block 182 via wire 180. This block is used to store the unit widths of the characters of the nine different styles of the matrix drum. Each section is divided into two subsections, one for uppercase and another for lowercase characters. The combined action of a character identity code and a style shift code thus causes also the width of the character entered to be read from memory 182. This width is now transferred via wire 183 to a width accumulator 184 which keeps a continuous count of the total accumulated width of the characters and spaces as they are read and decoded. The accumulated width value obtained following a character entry is transferred simultaneously via wire 185 to section 193 of memory 194 and to adder 178 to be added to the rank value of the same last character entered via wire 177. The sum of these two values is the displacement value which is now transferred via wire 179 to memory register 188 and then via wire 189 to section 192 of memory 194, to be attached to the accumulated width just entered and

to any style shift present in the line affecting the selection of a matrix level, if it precedes the character in the tape.

The "bits" arrangement representing a character in memory 194 is as shown in FIG. 15. In this figure, 12 bits shown at 201 represent the accumulated width of all the characters preceding this particular character plus its own width. Fifteen bits shown at 200 represent the rank value of the character. Group 199 may represent identification bits attached to all characters of a line following a shift code. Bit 203 distinguishes a character to be flashed from a function code and other bits 202 may be used for special identification of peculiarities pertaining to a given character.

Such function codes as "end of line," "leading," etc., can be distinguished by the absence of the "flash" bit 203 and certain arrangements of bits of other memory sections. The purpose of attaching a bit combination representative of a certain style or a certain size to each character that follows a shift code in the tape is to make it possible to produce at a high rate of speed all the characters of a line belonging to a certain drum level (or matrix row) and a certain size, leaving "holes" in the line for characters or words belonging to another font requiring a substantial access time. This method is more fully explained in our U.S. Pat. No. 3,273,475. In the following description of the control circuit shown in FIG. 10, the term "character" will mean all the bits representing a given character.

The rank value stored in memory 176 is independent of the selected drum level or matrix row. It depends only on the location of a character from the initiating pulse as explained above. The rank values for this embodiment are shown in FIG. 16. It can be seen in this figure that uppercase and lowercase characters are distinguished by the fact that lowercase characters have an even rank value while odd rank values identify uppercase characters. In this Figure the characters are represented in columns 254, the rank value of the first group of 102 characters around the drum are represented in columns 255 and columns 256 and 257 represent respectively the rank values of the second and third group of 102 characters. The shaded areas of the figure represent the location of drum ribs in which, of course, it is not possible to have characters. Although it has been assumed that these ribs are measured by an integral number of width units, it is clear that they can have any value.

The arrangement of characters is preferably determined by a computer because certain arrangements are better than others in that they affect the probability of having two or more characters of the same displacement or flash value. As characters not present at the same time within the angle 120 limiting the rectified arc cannot be simultaneously required to be flashed, they also cannot have the same displacement value. This is why the most frequently used characters in the English language: *e*, *t*, *a*, etc., are as widely spaced as possible. It is for a similar reason that uppercase and lowercase characters alternate in the sequence. As there are generally 34 characters within the projection angle 120, it is evident that the possibility of simultaneous flash of lowercase characters is decreased if only 17 of these 34 characters belong to this group.

Returning to FIG. 10, as explained in U.S. Pat. No. 3,273,475, the characters of a line to be composed are transferred from memory 194 via wire 195 to be sorted in the sorting circuit 196. After sorting, these characters are transferred via wire 197 to memory 198. During the sorting operation the characters are not only sorted according to their displacement or flash value, but they are further sorted according to their style and size as determined by the font identification attached to each character bit configuration. Thus, in memory 198, characters are arranged in different sections schematically represented by horizontal dotted lines, each section comprising groups of characters of a given style and size.

The end of a group of characters of a given font can be signalled by a special bit of memory for the purpose of initiating a style or size shift after all the characters of a given font have been flashed.

The sequence of operation described above occurs during the leading or line-spacing operation of the machine. The first character in the memory 198 is transferred via wire 203 from the memory to a first register 204 and via wire 205 to a second register 206 so that at the beginning of an active cycle of the machine the first character to be flashed will be stored in register 206 and the second character in register 204. As soon as the matrix mark 108 has generated a pulse representing the beginning of a new passage of all the characters of the drum within the arcuate projection zone 120 (FIG. 3) a counter 222 is restored to the value "1" and the timing pulses generated by marks 106 are channeled through gate 220 and wire 221 to counter 222. A comparison circuit 224 continuously compares the displacement value stored in block 206 via wire 225 to the value shown in counter 222 via wire 223 and when equality is obtained a gate 208 is opened. This gate allows a pulse to reach the unblanking circuit 212 of the flash-generating CRT via 209, delay 210 and wire 211 after a short delay sufficient to allow the potential across the deflection plates of the CRT to be effective.

The comparison circuit causes also a correction value stored in block 228 to be transferred via wire 229 to adder 230 which receives also through wire 207, gate 208 and wire 231 the accumulated width value associated with the first character to be flashed. The purpose of the adder 230 is to correct the horizontal deflection of the CRT to compensate for any lack of linearity between the angle by which the CRT must be horizontally deflected to illuminate a given area of the drum and the angle at which this illuminated area of the drum is located in relation to the optical axis of the machine.

After the horizontal deflection value has been corrected in adder 230 this value is transferred via wire 233 to a digital-to-analog converter circuit 234 and finally to the horizontal deflection circuit 236 of the CRT. As mentioned in the U.S. Pat. No. 3,273,475, it may be necessary to flash within very short intervals characters having the same displacement values. It is for this purpose that two registers 204 and 206 are preferably utilized in order to minimize the transfer time of a character to register 206. It has been assumed in the present example that the circuitry is fast enough so that if two characters appearing at a certain time in registers 204 and 206 have the same displacement value these two characters are projected with only a few microseconds delay. Practical experience shows that in the few occurrences where characters have the same displacement value these characters can be projected within the time the counter 222 shows the same value. This time corresponds to a displacement of the matrix drum of 1 unit. In one embodiment of the invention, the drum circumference measures 10,800 units. If the speed of the drum is 10 revolutions per second the passage of 1 unit corresponds to approximately 9 microseconds. Thus within 9 microseconds characters of the same displacement value can be projected without special circuitry. The time delay between the successive projection of characters of the same displacement value is conditioned by the speed of the controlling circuit of the CRT and the transfer speed of information from memory 198 to register 204 and register 206. The unblanking circuit 212 when it is energized sends a pulse by wires 240 to the control circuit 242 of the memory 198 and the character registers to call for the next character in storage. In the case where there are more characters to be flashed at approximately the same time than can be accommodated within the few microseconds elapsing between two consecutive timing pulses, the comparison circuit 224 recognizes the fact that the value in counter 222 is larger than the value in register 206 and generates a signal over wire 248 to a control circuit 250 causing the "missed" character to be returned to storage via wire 252. This character is returned into the memory unit, for example, at the same position where it was and the next character to be projected is called for by the control circuit of the memory 198.

As mentioned above, each character and machine function stored in the machine after being decoded is further identified by a distinguishing a character to be projected from a machine

function. These bits representing characters to be flashed are recognized by the buffer decoder 172 which sends a pulse on wire 260 to counter 262 to store the number of characters to be projected. Each time a character is projected by unblanking the CRT through energization of unblanking circuit 212, a pulse is directed through wires 240 and 244 to counter 262 to step it down 1 unit for each flash produced. Although this system is not necessary, it provides a checking means to ascertain that all the characters of a line have been projected before the counter 262 is returned to zero, producing at this point an output pulse on the wire 263 to release the end-of-line functions of the machine. As long as counter 262 is not returned to zero the photographic cycle continues. In this case, through a switching circuit not shown, when the "end-of-line" code is recognized by the function register decoder 246, the control 242 causes the memory 198 to be scanned again to hunt for the missing character. This missing character may be the recycled character which has the same flash displacement value as several other characters.

As it is desirable to flash all the characters of a given matrix row before shifting to another row in a line containing characters located in different rows or levels, several counters like 262 could be used, one for each row. In this case these counters store the number of characters of each row as they are read from the tape and the same sequence is used to store these characters in memory 198.

It is evident that other means can be utilized to handle the occurrence of missing characters, and the above has been given as an example only. It is clear from the foregoing description that the horizontal deflection of the CRT or the positioning along the path of a character row of a luminous patch is determined by the displacement value associated with a character which depends on both the location of the character along a matrix row and the accumulated width of the preceding characters in the line to be composed. The vertical deflection circuit positions the light patch at the level of the selected row on the matrix drum.

It is desirable in a machine as described to utilize as small a portion of the rectified arc as possible because of residual distortions more apparent for characters located at the extreme end of this arc. The maximum length of line obtained by a given rectified arc is proportional to the point size or enlargement ratio of the projected characters, as is shown in FIG. 11. In this figure the rectified arc is limited by points 270 and 272. The length of this arc is shown as measuring "C" units. The film is shown at 66 and its width (8 inches, for example) is represented by reference number 269. If the arc measures 5 inches after optical rectification, it will be projected outside the film area between points 271 and 273 as shown in the figure if a lens 275 of a sufficient enlargement ratio is utilized. In the example of the figure it is assumed that the matrix is provided with 6-point characters and that the lens 275 produces 18-point characters on the film. In this case the distance between points 271 and 273 measures 3×5 or 15 inches, and the first characters of a line would fall outside the film area if they were projected at the extreme limits of the rectified arc. For this reason, and in order to obtain the best possible quality of the projected images, a circuit is provided to automatically center on the optical axis 39 lines of any length and of any size.

In FIG. 11 it is assumed that the matrix characters are continuously moving in the direction of the arrow 268. In this case, point 270 corresponds to line 124 of FIG. 3 and point 272 corresponds to line 122 of the same figure. It is further assumed in FIG. 11 that LL represents the length of the line to be projected. As it can be seen in the drawing the line LL is limited by point 274, conjugate of point 276, and point 278, conjugate of point 280 of the matrix. So the first character of this line will be flashed at the time its reference line cuts point 276 and moves beyond this point by a distance equal to its width. Likewise the last character of the line will be projected so that its right-hand reference line or edge will be projected at point 278 on the film, at the moment the same character

reaches point 280. In order to be always in the best projection condition as mentioned above, a delay represented in the matrix plane by the distance " D " must be introduced following the initiating pulse indicating the beginning of a new sweep and any character to be projected. The result is the same as though the rank value of the characters were changed to accommodate a new starting point.

This distance " D ," expressed in machine units, can be determined as follows: $D=(C-A)/2$ where "C" is the length of the rectified arc comprised between points 270 and 272 and "A" is the length of line LL multiplied by the inverse of the magnification ratio or $A=LL \times 1/E$ where E is the magnification ratio. For 6-point matrix characters $E=S/6$ where S represents the the point size of projected character images and $A=6LL/S$. But $6LL/S$ represents the length of the projected line in relative units of this line, that is in fractions of an em of the point size of this line, because $6LL$ represents the length of line in "absolute" units of one-eighteenth of a point and this divided by the point size in use does represent the length of line in units relative (ru) to the size in use. So finally: $D=C-LL(ru)/2$ where D and C are in machine units (relative to 6 points) and LL is in relative units of the projected size. It is clear from the above that for any point size and any length of line the deficit " D " is known and can be electronically generated. The operation of the control unit given as an example only to automatically produce this condition is shown in the block diagram of FIG. 12. In this diagram block 246 represents the function register. The desired length of line expressed in relative units of the point size of the line to be projected is transferred via wire 283 from the function register to a subtractor 284. This length of line is subtracted from the fixed value expressed in machine units (relative to 6-point) of the arcuate projection zone, stored in block RAS 286 connected by wire 287 to the subtractor 284. The result of this subtraction which is actually the numerator of the above-defined fraction is transferred via wire 289 to a divider 290, to be divided by 2 so that the actual deficit D by which the timing pulses should be delayed is transferred via wire 291 to register 292 and then via wire 293 to a counter and gate 294 connected by wires 295 to the main circuit of FIG. 10. Counter 294 is thus set up at a value equal to the value D of the above formula expressed in machine units and this counter is stepped down by pulses generated by the marks 106 of the pulse generator disc 104 (FIG. 2) of the machine as soon as the initiating pulse is generated. This countdown starts at the exact time when the left-hand reference line of the first character (as defined in FIG. 3) crosses point 270 of FIG. 11. The pulse generator associated with disc counts down the values stored in counter 294 and when this counter is returned to zero a pulse appears on wire 295 to activate the projection and selection circuits of the machine. All the character projections are thus delayed by D machine units. At the end of a revolution of the drum the initiating pulse energizes reset flip-flop 296, which via wire 298 resets 292 to zero, in case a new value has to be entered for the next line. This value as shown, depends entirely on the value stored in function register 246 representing the length, in relative units of its size, of the line to be projected. As long as the relative length of line is not changed the function register shows the same value. This value is changed only when the new length of line is transferred to the function register from the main storage of the machine following a length of line shift code.

As it is clear from above description, the automatic delaying circuit will center each line on the axis of the optical projection system regardless of the selected length of line or point size. This is done by delaying the projection of the first character of the line by a time interval which is dependent upon the selected point size. As it may be desired to align lines of various sizes on the left-hand margin, provisions must be made when the text is composed to compensate for the various starting positions of different lines in relation to the left-hand margin by inserting the proper amount of spacing at the beginning of certain lines.

The same result can also be automatically obtained as described in relation with FIGS. 13 and 14. In FIG. 13, as in FIG. 11, the rectified arc is represented by "C," comprised between points 270 and 272 representing respectively as mentioned above the end and the beginning of the projection area. The film is shown at 66 and it is preferably centered on the optical axis 39 as shown. Distance "J" represents the maximum length of line that can be obtained with the machine. A large size lens such as 275 which would produce an enlargement of 3 would place the first character of the line flashed at position 270 at its conjugate point 271 in the plane of the film. As the film is not wide enough to receive this image it is desirable to automatically delay the beginning of the character projection cycle by a value DA .

The following explains how the value DA expressed in machine units is determined.

$DA = (C/2) - J/2E$ where C represents the rectified arc, J the maximum length of line the film can accept and E the enlargement ratio, but $E=S/6$, for 6-point matrix characters; so $DA = (C/2) - (6J/2S)$. Now $C/2$ is a constant value K_1 and $(6J/2)$ is another constant and known value K_2 . So $DA = K_1 - (K_2/S)$.

An example of the circuitry which can be used to carry out the above computation is schematically shown in the block diagram of FIG. 14 in which the function register of the machine is shown at 246. Whenever the function register reads and recognizes a point size shift, the new value of the point size expressed for example in binary form is transferred via wire 303 to point size storage 304 until a new point size value is entered into this storage. The value stored in block 304 is the value represented by "S" in the above formula. This value is transferred via wire 305 to a divider 306 to be divided by the constant value K_2 stored in block 308. The result representing the number of times the maximum length of line "J" expressed in units and multiplied by 3 contains the number representing the point size may not be an integral number. In this case the units smaller than 1 (or one-half) machine units are ignored and the result is transferred via wire 309 to subtractor 310 to be subtracted from the constant value K_1 stored in block 312. The result of the subtraction is finally transferred via wire 315 to register 315. In the case where the subtraction could not take place because the point size selected is too small to accommodate the maximum length of line J a signal is generated by the subtractor 310 over wire 313 to signify a program error. This case could occur if a small size lens such as 277 (FIG. 13) is selected. The projection of point 270 would fall at 270' which is well away from the margin of the film, toward the center of the film.

In one embodiment of the invention, the values of the rectified arc and the lenses and the maximum length of line are so selected that this condition occurs only for point sizes smaller than 8-point. It is possible to avoid this difficulty by offsetting small point size lenses to place their optical axis or center on the line 270-279 connecting the "earliest" possible projection point 270 of the matrix plane to point 279 representing the left-hand margin of the film as indicated by 277'. In this case no correction of lines which would otherwise be too short is necessary, and the delay DA will be systematically ignored.

In the embodiment described herein, the matrix drum is provided with three rows of different characters located at levels 32, 38 and 42, as shown in FIG. 1. According to one important feature of the invention, the selected characters of these different rows can be projected to the same baseline on the film without moving the character drum up or down or displacing an optical system. The selective illumination of a character row is obtained by controlling the vertical deflection of CRT 46 as stated above.

As shown in FIG. 1, characters of row 32 can be projected along optical path 33, to make an image at location 34 on the film. The light bundle representing characters of the central row 38 are approximately centered on the optical axis 39 of the machine and are projected at location 40 on the film. The

lower row of characters 42 are projected along path 43 to reach location 44 on the film. The distance between locations 34 and 44 depends, of course, on the optical leverage of the lens, that is on the magnification of the optical system or on the point size of the character projected. It must be pointed out here that the characters of the central row intersected by the optical axis will be projected on the same baseline on the film regardless of the point size or magnification ratio. In order to obtain this result for various point sizes, the different lenses of the turret must be accurately positioned. In order to align characters of any row on the same baseline without moving the drum the film must be moved forward or backward by a distance depending on the selected row and also on the point size of the projected character images, as explained more fully hereinafter.

The specific arrangement herein described can be modified without departing from the scope of the invention. The CRT can be replaced by any other means of displaying a light area at a given point for a very short time and at a fast rate. It is possible, for example, to use a continuous laser as a light source associated with voltage-sensitive crystals, cylindrical lenses and an electrooptical shutter. The crystals are utilized to deflect the laser beam to a given area of the cylindrical lens arrangement and the purpose of the electrooptical shutter is to produce extremely short flashes. Another approach would be to use a multiplicity of flashlamps having light-directing means associated therewith such as a plurality of light pipes. Both the laser and the flashlamp embodiments will be more fully described hereinafter.

The timing pulses can also be generated by an oscillator periodically "framed" by synchronous pulses associated with the drum.

If a multiple-gun CRT is used, the guns can be alternately energized for successive flash commands, leaving thus more time for each individual gun deflecting circuit. It is also possible to operate several guns simultaneously in order to increase the brightness of the luminous spot.

In the embodiment described in FIGS. 17-20, the matrix drum is provided with three rows of different characters located at levels 32, 38 and 42, as shown in FIG. 1. According to one important feature of the invention, the selected characters of these different rows can be projected to the same baseline on the film without moving the character drum up or down or displacing an optical system. The selective illumination of a character row is obtained by controlling the vertical deflection of CRT 46.

As shown in FIG. 1, characters of row 32 can be projected along optical path 33, to make an image at location 34 on the film. The light bundle 39 representing characters of the central row 38 are approximately centered on the optical axis of the machine and project characters at location 40 on the film. The lower row of characters 42 are projected along path 43 to reach location 44 on the film. The distance between locations 34 and 44 depends, of course, on the optical leverage of the lens—that is, on the magnification of the optical system or on the point size of the character projected.

Turning now to FIG. 17 the location of character "M" on the film for different rows is shown for a large point size such as 18 points on the left-hand side of the figure at 400 and a small size such as 6 points, on the right-hand side of the figure at 402. It must be pointed out here that the characters of the central row intersected by the optical axis will be projected on the same baseline on the film regardless of the point size or magnification ratio. In order to obtain this result for various point sizes, the different lenses of the turret must be accurately positioned. In the description which follows, it is assumed that the relative character position on the film is measured from a line 404 which is the baseline of the largest point size of which the machine is capable, for example, 18 points. In order to align characters of any row on the same baseline without moving the drum the film must be moved forward or backward by a distance depending on the selected row and also on the point size of the projected character images to

compensate for the character displacements illustrated in FIG. 17.

The film displacement or leading mechanism of the machine is schematically shown in FIG. 18. In this figure the shaft 406 connected to the film drive roller 88 of the film magazine shown in FIG. 1 is the output shaft of a differential arrangement. The two inputs of said differential are respectively controlled by stepping motors 408 and 410. The stepping motors and the gear ratios 412—414, and 416—418 are so selected that 1 increment of 1 step of motor 408 will cause shaft 406 to rotate by an amount corresponding to 14 leading increments while 1 step of motor 410 will cause the same shaft to rotate by 1 leading increment. The leading increment has been selected to be equal to one-seventh of a typographical point of 0.05 mm. All the leading or film displacement values of the machine are expressed in integral numbers of leading increments. The primary purpose for using two stepping motors connected by a differential in this mechanism is to decrease the leading time by simultaneously operating the two stepping motors capable of giving large and small film displacement values rather than by actuating one single stepping motor which would be required to produce a rather large number of steps for each film displacement. The stepping motors are controlled by a stepping motor control or translator 420.

Returning now to FIG. 17, assuming that the characters of the three different rows are projected without displacing the film, these characters represented by letter "M" would be located as shown in group 400 for point size 18 and as shown in group 402 for point size 6. In order to align all these characters on the same baseline without changing the relative position of the matrix and the optics, it is necessary to move the film up or down by an amount depending, as stated above, on the point size in use, the character row in use, and the previous selection of these parameters for a new selection. Suppose, for example, that after characters of the central row 38 of FIG. 1 have been projected in 18-point it is now desired to project characters of upper row 32 falling on baseline 404 of FIG. 17, on the same baseline as the previously projected characters. To obtain this alignment it is necessary to move the film down (as shown in FIG. 17) by a distance L2 in order to bring the characters originally projected on baseline 422 onto the baseline 404 of the characters to be projected. If now it is desired to shift characters from row 32 to row 42, as the characters of row 42 are aligned on baseline 424 it is necessary to move the film upward by a distance L3 in order to bring the characters previously projected at baseline 404 onto baseline 424. The baseline 404 of the largest size characters of the row 32 is taken as a base to determine the actual location of character images, and consequently to determine the amount by which the film should be moved up or down in anticipation of the projection of characters belonging to a different row or corresponding to a different size.

It must be pointed out here that the distance L2 between the baseline 404 of the largest character of row 32 and the baseline 422 representing the intersection of the optical axis of the machine with the film as well as with the baseline on which the characters of the central row are projected, is invariable, because all the lenses of the turret are so positioned that their optical axis, when they are in use, intersect the baseline of characters in row 38. If the different rows of the matrix drum are separated from character base to character base by 3 millimeters, this distance corresponds to 60 leading increments of 0.05 mm. each. If we assume further that the matrix characters are 6-point characters, distance L2 for 18-point characters will be $3 \times 60 = 180$ leading increments.

The distance between line 404 and the baseline of characters of different rows and sizes is shown in the table of FIG. 19. In this table SI represents the various point sizes the machine can produce and columns L1, L2 and L3 represent respectively the distance from line 404 to characters of various sizes as represented by columns SI for rows 32, 38 and 42. The table of FIG. 19 has been obtained as follows: If X is the distance

from the central baseline 422 to the baseline of characters of a given size, this distance is equal to 60 leading increments (representing the distance between two consecutive rows on the drum) multiplied by the enlargement ratio, which is defined as the ratio between the size of the projected characters to the size of the matrix characters. For 6-point matrix characters X is equal, in leading increments, to 10 times the sizes in use. Thus the distance from baseline 404 of 18-point characters to central line 422 is equal to 180 leading increments. The value X is added to the distance L2 for characters located in the row 42 or subtracted from this distance for characters located in the row 32. For example, characters projected in 7-point will be distant from axis 422 by a distance equal to 70 leading increments. For 7-point characters of row 32 the distance from their baseline to line 404 will be equal to 180—70 or 110 leading increments (as shown in the table) or 180+70; that is, 250 leading increments for characters located in the row 42.

A circuit which may be used to implement the system just described is represented in FIG. 20. The function register-decoder of the machine is shown at 426. The purpose of which is to detect lens shift codes which are transferred via wire 428 to the lens turret circuit 430 and drum level shift code which are transferred to a table of stored values 432. Since in the example described we have assumed that the matrix drum is provided with three rows of characters, there can be three wires in group 434 connecting decoder 426 to the stored tables 432 in order to select one of the values of columns L1, L2 and L3 of the FIG. 19. The other value to be entered is dependent on the point size in use. In FIG. 20 the lens turret is controlled by lens turret circuit 430 which generates a number representing the point size. This number is transferred via wire 433 to point size storage 434. Ten wires 436 connect the point size storage 434 in the stored tables 432 for the purpose of selecting one of the horizontal rows of values shown in the table of FIG. 19. Wires 438 connecting the stored table block to the register 440 can transfer to this register any of the values shown in FIG. 19. The selected value is transferred through wire 442 and gate 444 via wire 446 to a storage block 448 at the beginning of the operation of the machine. This value is also transferred via wire 450 to a comparison circuit 452. When a new point size or drum level is selected, a new value is transferred to register 440 either immediately in the case of a matrix row shift or after the lens turret has assumed a new position in the case of a point size shift. The new film shift value is now transferred via wire 454 to comparison circuit 452 which is going to compare it to the previous film shift value stored in block 448. If the new value is larger than the previously stored value, a wire 456 is energized to cause the stepping motors to move the film up as shown in FIG. 18. If, on the other hand, the new value is smaller than the previously stored value, the wire 458 is energized to cause the film to be reversed and move down. These forward or reverse actions of the stepping motors are controlled by the translator circuit 420 as is well known in the art. The difference expressed in leading increments, whether positive or negative, is transferred by wires 460 to leading increment storage 462 and then to translator 420 in order to move one or both motors to cause the motors to produce a number of increments equal to the difference shown in storage 462. As the leading increment values are expressed in 1 increment of the "fine" leading motor this value is divided in circuit 420 by 14 in order to determine the number of pulses to be fed to the coarse leading motor. When the film displacement is complete, a signal is transferred over wire 464 to gate 444 to enter the new film displacement value into block 448. The purpose of the circuit is not only to align on the same baseline, characters of different sizes belonging to either the same or different matrix rows—it is also to preserve the established fixed leading of the machine independently of point size or matrix row shifts.

The operation of the system will further be illustrated by a few examples. Let us assume now that we begin a new text by a title or heading in 18 points using characters of the central

row 38 of the matrix. The film displacement value stored in block 448 will be 180 units, as shown in the table. We now shift in the same line to the row 32 of the matrix. The new film displacement value will be zero. The comparison circuit will detect the fact that this new value is inferior to the previously stored value of 180 units and will cause the film to move down by a distance equal to the difference between the previous value and the new one, that is 180 units. It can be seen by examination of FIG. 17 that this will cause line 422 on which characters of the first section of the line were projected to move down to the same level as line 404. If now the last characters of the same line are also 18-point, but belong to the lower row 42 of the matrix, the new stored value will be equal to 360 film displacement units. This value being larger than the previously stored value will cause the film to move up by a distance equal to 360 units which will bring the baseline 422 from position 404 to position 424.

Disregarding now the fact that there will usually be an amount of space between lines of different sizes let us assume that 6-point characters are utilized in the text following the heading. If these characters correspond to the upper row of the matrix drum, the new stored value will be equal to 20 leading increments. As the new value is inferior to the previously stored value which was 360, the film will be moved down by 240 units which will bring the baseline from position 424 to position 466. Thus the characters of the heading and the characters of the first line would be on the same baseline but in fact they will be separated by a distance determined by the preselected line spacing or leading of the machine.

The line-spacing value is generally stored in the control tape although it can also be manually selected and directly entered into the machine. The line-spacing value as determined by the decoder 426 is stored into leading storage 470 by wires 468. This value is not changed as long as a new leading value is not transferred to this block. When the function decoder 426 decodes a zero lead signal it operates gate 472 through wire 474 to prevent the leading value of block 470 to be effective at the next end-of-line. Gate 472 is normally operated by wires 476 energized by the function decoder upon the detection of end-of-line signal in order to transfer the stored leading value to the stepping-motors controlling circuit.

The selected matrix drum level is stored in block 478, for example in binary form. The values stored in block 478 is connected by wires 480 to a digital-to-analog converter for the purpose of controlling the vertical deflection plates of the CRT, to illuminate the matrix level corresponding to the value represented by block 478.

Thus, means are adapted to variably displace the film or image-receiving surface in conjunction with a style shift and/or a point size change, in order to compensate for relative displacement which may occur between the film and the characters which are being projected when a style shift occurs, when the point size is changed, or when style and size are changed simultaneously, in order to ensure a common baseline.

In a machine provided with a turret carrying lenses of different focal lengths, means should be used to equalize the amount of light falling on the film for the various point sizes, as it is evident that an 18-point character will require more illumination than a 6-point character to produce the same density on the film. This result can be achieved by using diaphragms in the lenses, as is known in the art, or by increasing the acceleration of the electron beam. It may also be desirable to increase the light intensity of the light patch as it moves away from the optical axis. This increase could be controlled by the accumulated width value which actually represents the position of the light patch as it moves from one extreme of the rectified arc to the other.

In the embodiments depicted in FIGS. 21-45 of the drawings, the present invention provides character illumination means capable of emitting light flashes of extremely short duration—making it possible to reduce the exposure time to 1 microsecond or less—thereby further increasing the speed of 75

the machine. The illumination source may comprise a multiplicity of flashlamps, or one or more laser sources. Well-defined light patches are produced at a plurality of discrete positions within the arcuate projection zone by interposing a plurality of light-directing means such as light channels or pipes between the illuminating source and the zone. Each light channel is associated with a flashlamp or other source of illumination capable of illuminating discrete areas of the zone. In other words, discrete light patches are produced where they're needed, when they're needed.

Referring to FIGS. 21 and 22 of the drawings, a multiplicity of light channels 500 are positioned side by side, and are affixed at their output ends to a movable support or holder 502. A total of 26 light channels are shown. Holder 502 is pivoted around collar 504 which is coaxial with drum 20 (see FIG. 1). Holder 502 is provided with an arcuate rack 506 engaging a pinion 508 driven by stepping motor 510. The flashlamps are arranged in two banks or rows, each having 13 lamps. It is understood, of course, that the drum, optical system, film and all related equipment shown in the prior figures are also applicable to the embodiments of FIGS. 21-45, unless otherwise stated.

Referring to FIGS. 24-27, as well as to FIGS. 21 and 22, each light channel 500 includes a solid light pipe portion 512 and a flexible light pipe portion 514, which are associated with flash units. In this embodiment there are 26 light channels and 26 flashlamps, designated 515-1 to 515-26 in the drawings. It should be understood however, that the number of lamp-channel units may be varied if desired.

Each light channel 500 is preferably constructed as shown in FIGS. 24-27 where 514 represents a flexible pipe of fiber optics which is positioned within coupling sleeve 516. Flexible pipe 514 is butted or cemented to pipe 512, which may be a solid material such as glass or plastic. The alignment of pipes 512 and 514 is achieved by positioning both of them within light pipes coupling sleeve 516 (See FIG. 25). Each solid pipe 512 is provided with a pair of triangular roofs or protrusions 518 in order to accurately position these pipes in relation to the arcuate projection zone of matrix drum 20, as represented by rectified angle 120 (see FIG. 22). This positional accuracy is ensured by cutting triangular grooves in extending member 520 of holder 502, as shown in FIG. 27. A fiber holder cover 522 contains a series of identical triangular grooves such that each solid pipe 512 is secured between complementary grooves. Similarly, in order to enhance positional accuracy, lugs 524 of coupling sleeve 516 engage mating grooves formed in the other side of extending member 520 (see FIGS. 24 and 25) of holder 502.

Turning now to the opposite end of the light channels 500, (see FIG. 22) each flashlamp 515 comprises a flash portion 526, and trigger-flash circuitry 528. If desired, it may also include an optical condenser (not shown). Extension 530 of flashlamp 515 is slotted as shown in order to give it sufficient elasticity to enable it to hold a contiguous fiber optics pipe 514 by friction. Each of the 26 flash units are secured to the frame 26 of the machine via plates 532 and 534.

Characters may be equally spaced on the matrix strips 30, as previously described, and as depicted in FIG. 23 of the drawings. What will be termed a "maximum character area" is numbered 540 in FIG. 23. Each character is accurately vertically positioned in each character area 540 so that the character rests on a baseline 542—this baseline is preferably common to all of the characters of the matrix. Each character is also accurately positioned in relation to a "left-hand reference line" 544. These lines 544 are to physically reproduced on the matrix—they are used by the type designer to accurately space characters relative to one another. These reference lines may also be referred to as the "left-hand margin of a character."

Character areas are equally spaced (measured from one "left-hand margin" to the next) by a distance 546. Each character area width 548 is large enough to accommodate the widest character in the array. The maximum character areas

540 are also equally spaced from one another by a distance 550. As shown in FIG. 3 of the drawings, the matrix 30 moves in the direction of arrow 6.

FIG. 28 is a schematic representation of the fact that the output assembly (i.e., solid pipes) 512-1 to 512-26 of light channels 500 are movable among three different positions. Position No. 1 is designated 560, position No. 2 is numbered 562, and position No. 3 is shown at 564. Each of pipes 512 may be 39 units wide. The pipes may be moved in unison 13 units from position No. 1 to position No. 2 to position No. 3 and are then returned to position No. 1. The small incremental angular displacement (i.e., 13 units at a time) is made possible by flexible pipes 514-1 to 514-26 connecting the fixed flash assembly to the movable portion of the light channels (see FIG. 22). The pipes 512, which are mounted on holder or carriage 502, are moved from one position to the next following each complete revolution of the matrix drum. Although the light channels are movable among three discrete positions relative to the arcuate projection zone in this embodiment, it is apparent that the number of positions may be varied. For example, in another embodiment described hereinafter, the light channels are movable between two discrete positions. In general, the greater the number of light channels, the less they will have to be moved in order to properly illuminate the projection zone. Thus in the embodiment of FIGS. 34-40, a larger number of light channels are fixed. Likewise, it would seem feasible to have only a few light channels which would be moved to many different positions. It is quite apparent that all of the aforescribed modifications are within the scope of the present invention.

The "zero unit position" represented by a line marked "O.U.P." in FIG. 28, represents the "start" line of the projection zone of the matrix. Thus, an extremely thin "character" (a hairline, for example) tangent to the left-hand margin of a line would be projected at the precise moment it cuts this predetermined reference point, as has been fully described in previous embodiments.

Referring now to FIGS. 29-33 of the drawings, a sample line of composition will be examined, in order to afford an example of the three-position embodiment of the invention. The sample will be: "Photon, Inc., Wilmington, Mass." As has been explained previously, each character is assigned a rank value in accordance with the position in which it is located on the matrix. As shown in FIG. 30, the rank value of "A" is 39—that is, "A" is positioned 39 units from the starting point or predetermined reference point on the matrix. Next, "a" has a rank value of 78 units, "K" 1,053 units, and so forth. Certain characters which appear frequently in a text, such as "e" and "o," appear twice in a given character "alphabet." This is indicated by the hatched lines in FIG. 30.

FIG. 31 is a comprehensive table which sets forth all of the factors involved in properly spacing and flashing the characters, with the exception of the flash sequence, which is set forth in the table of FIG. 32. Each character has a certain width relative to the rest of the characters of the alphabet. For example, the character width of the "P" is 14 units, the "I" is 11 units, and so forth. Also, the accumulated widths of the previous (or succeeding) characters in the line as composed must be taken into account in arriving at the "flash value" for each character. For example, as is apparent from FIG. 31, the accumulated widths of the characters appearing before the "i" in "Photon" is 33 units, and for the "M" in "Mass." this figure is 221 units.

Also shown in FIG. 31 are bundle positions Nos. 1, 2, and 3, as well as the flash unit numbers for the various characters. This portion of the table shows which flash unit will illuminate a given character, as well as in which of the three bundle positions the unit will be when the character is flashed. For example, the "h" will be flashed by unit No. 1 (512-1 in FIG. 29) in bundle position No. 2.

The "flash value" for each character is the sum of the rank value of the character, and the accumulated widths of the previous characters in the line when composed. Thus, the "a" 75

has a rank value of 78 units, and the accumulated width is 239 units, thereby resulting in a flash value of 317 (i.e. 239+78) units. It will be noted that the characters which are repeated (as indicated by the hatched lines in FIG. 30) have both a "normal" and an "alternate" rank and flash value. Each flashlamp has a 600-microsecond "rest time" between flashes. Therefore, the alternate flash value is used only when a certain lamp would otherwise be required to flash twice in less than 600 microseconds. One instance of this would be the word "Mass." If normal flash values were used for "ss," flash unit No. 7 would be required to flash twice in bundle position No. 2 within 7 units (that is, flash values 2,198 and 2,205). Therefore, the alternate flash value of 1,503 units is used for the second "s," thus allowing flash unit No. 7 its usual rest time.

The "retained flash value" portion of the table in FIG. 31 sets forth the end result of the remainder of the table. It should be noted that the values in parentheses indicate that an alternate, rather than a normal, flash value is used.

The flash channel and bundle position at which a selected character is to be flashed depends upon the position of the character in the composed line—in other words, on the accumulated widths of the preceding characters in the line. The table of FIG. 32, which is a tabular representation of the "unit positions" set forth graphically in FIG. 28, should be examined together with the sample of composition in FIG. 29. It will be seen that the "accumulated width value" for each character determines the flash channel and bundle position at which it will be illuminated. For example, the "W" (having an accumulated width value of 113 units) will be illuminated by flash channel (or unit) 3 at bundle position No. 3.

The table of FIG. 33 depicts the flash sequence or order in which the characters will be flashed. It is clear that the characters are not flashed in the same sequence in which they appear in the composed line. The ability to flash the characters as they appear on the matrix, rather than in the composed line, greatly increases the speed of composition of the machine.

The embodiment of the invention depicted in FIGS. 34-40 of the drawings is similar to the last-described embodiment; however, the light channels are fixed, not movable. As before, (see FIG. 22), the light-directing means comprise a plurality of light channels each having a first end adjacent to the illuminating means, to receive light emanating from the sources, and a second end in close association with the arcuate projection zone, for directing light emerging from each of the light channels to a discrete position within the zone. The light channels are positioned relative to one another in such a manner that the second ends terminate at locations which are equidistant from the zone.

Turning to FIGS. 34 and 35, a plurality of light channels 600-1 to 600-41 are shown. The channels are fixed in a holder 602 which is secured to frame 26 of the machine. The flashlamps 604-1 to 604-41 are identical to lamps 515 previously described (see FIG. 22), except that each lamp 604 has a condenser 606 associated therewith. In this figure there are four (vice two—see FIG. 21) rows of flashlamps. The lamps are secured to frame 26 by holding plates 608 and 610. It is apparent that the arcuate projection zone as depicted by angle 120 is of sufficiently large dimensions to include a plurality of master characters at any given time as the characters pass through the zone. The actual number of characters which can be accommodated within the zone at any given time depends upon the spacing between characters, the point size of the characters, and the field-flattening characteristics of the optical system. As has been previously pointed out, it is undesirable to project a character when it is located at the extreme ends of the zone.

FIG. 36 depicts the previous sample of composition "Photon Inc., Wilmington, Mass." as it would be flashed using the fixed channel embodiment. It is clear that some of the characters, such as the "h" and the "W" will overlap two adjacent light channels at the time of projection. It is necessary therefore, to simultaneously illuminate these light channels at the proper time. FIG. 37 is a front view of the light channels

600, and FIG. 38 is a plan view thereof. In this embodiment, the characters are spaced by 40 units. Since the flash of each channel tends to spread (as indicated by hatched lines 620 in FIG. 37) through a flash spread angle 622, a lenticular diffusing material 624 is positioned between channels 600 and the character areas 118 of matrix 30 in order to ensure uniform distribution of light in the overlapping areas between adjacent channels, when two adjacent channels are simultaneously illuminated. Each channel 600 is 18 units wide, and the flash spread area 620 is 2 units wide, or 4 units for each channel. Thus, the light channels are fixed and the illuminating means are adapted to transmit light simultaneously through two adjacent light channels in order to properly illuminate a selected character when it overlaps two discrete positions within the projection zone, the discrete positions being formed by light emanating from two adjacent light channels at the time of projection of the selected character.

Returning to the sample line of composition, the flash sequence depicted in FIG. 40 is arrived at in the same manner as heretofore, except that there is only one bundle position, since the channels do not move. Once again, the flash channels for each character (see FIG. 39) is dependent upon the accumulated widths of the previous characters in the composed line (see FIGS. 29 and 36). The table of FIG. 31 is again applicable, except for bundle positions. A glance at the flash sequence of FIG. 40 indicates, for example, that the "W" has a flash value of 2,414 and will be flashed by light channels 7 and 8.

As before, composing speed is significantly increased because characters are flashed "as they come." This embodiment of the machine allows a complete line to be composed during a single revolution of the drum. As mentioned previously, all of the character storage, sorting and related computations are performed by the computer control means which has heretofore been described in detail.

FIG. 41 depicts an embodiment of the invention in which the light channels 650 are movable in unison between two discrete positions. In this case each channel is 48 units wide, and moves 24 units from position No. 1 to position No. 2, as opposed to the "three-position" embodiment of FIG. 28. The computer control circuitry which has been previously described in detail may, of course, be used to properly project characters onto the film.

The matrix 660 of FIG. 42 should be compared to matrix 30 of FIG. 23. Although the clearance between character areas (designated 550) is the same, the maximum character areas 540 of FIG. 23 are replaced in FIG. 42 by variable character widths such as 662 and 664. Thus in FIG. 42 the distance from the left-hand reference line of one character to the next will vary, whereas the corresponding distance 546 in FIG. 23 is constant. In FIG. 42 therefore, the rank value may vary from one character to the next because the value depends upon the intercharacter spaces, as well as on the accumulated widths of the previous characters of the matrix 660. The advantage of the matrix of FIG. 42 is that the number of characters carried by a matrix of the same dimensions as heretofore may be increased, since the average character is 9 units wide, whereas each "maximum character area" must be 18 units wide, i.e., large enough to accommodate a capital "M," the widest character in the alphabet.

The embodiment of the invention depicted in FIGS. 43-45 is quite similar to the "fixed light pipes" embodiment previously described, except that the source of illumination is a pair of lasers rather than flashlamps. Light from a pair of lasers 700 and 702 passes through polarizer 704 to deflector 706, which includes a plurality of electrooptic crystals 708. Beam-deflecting crystals 708 are controlled by the computer control means, as is the rest of the system. The light beam then enters the eight-level light channel input face 710, after which it is transmitted to the projection zone via one of light pipes 712-1 to 712-41, and from there to film 718 (mounted on film rails 720) via lens 714 of lens turret 716.

As mentioned previously, the light channels are fixed and lines will be composed as in the embodiment of FIGS. 34-40, using an identical flash sequence, if desired. As before, when a selected character overlaps two adjacent light pipes at the time of projection, lasers 700 and 702 are energized simultaneously. Light is conducted to adjacent faces, for example, to 710-5 and 710-6 of FIG. 45 in order to properly illuminate the selected character. The arrangement shown in FIGS. 3 and 38 would preferably be employed in order to ensure uniform light distribution. If desired, a single laser source may be used, but of course the speed of composition would be somewhat reduced.

The foregoing description is intended to be illustrative only. Various changes or modifications in the disclosed embodiments may occur to those skilled in the art. It is understood, therefore, that all such modifications as would be apparent to one skilled in the art are included within the scope of the present invention.

What is claimed is:

1. A photographic type-composing machine comprising: a rotatable character-carrier having a curved surface bearing master characters to be projected, a surface for receiving projected images of said master characters such that lines of composition may be composed on said image-receiving surface, an arcuate projection zone of sufficiently large dimensions to include at least two master characters at any given time as said characters pass through said projection zone, an optical projection system for projecting an image of the arcuate projection zone to said image-receiving surface, said optical projection system including optical means adapted to project the arcuate projection zone as if it were flat, so that an undistorted image of said zone may be produced on the image-receiving surface, means for illuminating any one of the master characters while said character is in the projection zone, and control means to vary the time at which said illuminating means is energized such that a selected character may be illuminated at any given time as it passes through said projection zone, in order that the projected images of said characters comprising a line of composition may be spaced from one another according to their respective widths.
2. The machine of claim 1 in which said illuminating means includes a high-intensity light patch dimensioned to illuminate one master character at a time, said light patch being movable to different positions within said projection zone by the energization of beam-deflection circuits controlled by said control means.
3. The machine of claim 2, in which the illuminating means comprises a laser having associated beam-deflecting crystals controlled by said control means.
4. The machine of claim 2 in which said illuminating means comprises a CRT having a screen of high actinic value.
5. The machine of claim 4 in which the CRT has more than one electron gun.
6. The machine of claim 4 in which an optical fiber screen over the front of the cathode-ray tube screen transmits light from the cathode-ray tube screen to the projection zone.
7. The machine of claim 6 in which the optical fibers are positioned relative to one another such that their ends which are remote from the cathode-ray tube screen terminate at locations which are equidistant from said arcuate projection zone.
8. The machine of claim 4 in which a collimating lens is disposed adjacent to the cathode-ray tube screen, and a second lens is adapted to focus light emerging from said collimating lens to a focal point of the optical projection system.
9. The machine of claim 1 in which said illuminating means have associated therewith means for directing light emanating from said illuminating means to a plurality of discrete positions within said arcuate projection zone.
10. The machine of claim 9 in which:

said light-directing means comprise a plurality of light channels, each of said light channels having a first end adjacent to said illuminating means for receiving light emanating therefrom, and a second end in close association with the arcuate projection zone for directing light 5 emerging from each of said light channels to a discrete position within said zone.

11. The machine of claim 10 in which said plurality of light channels are positioned relative to one another in such a manner that said second ends terminate at locations which are 10 equidistant from said arcuate projection zone.

12. The machine of claim 9 in which said light-directing means is movable.

13. The machine of claim 12 in which:

said light-directing means comprise a plurality of light channels, each of said light channels having a first end adjacent to said illuminating means for receiving light emanating therefrom, and a second end in close association with the arcuate projection zone for directing light 20 emerging from each of said light channels to a discrete position within said zone.

14. The machine of claim 13 in which each of said light channels is flexible.

15. The machine of claim 13 in which said light channels are 25 movable to a plurality of discrete positions relative to said projection zone.

16. The machine of claim 15 in which said light channels are movable in unison.

17. The machine of claim 16 in which said light channels are 30 movable in unison between at least two discrete positions relative to said arcuate projection zone.

18. The machine of claim 16 in which said light channels are movable in unison among three discrete positions relative to said arcuate projection zone.

19. The machine of claim 16 wherein said light channels are mounted on a movable support means.

20. The machine of claim 9 in which said illuminating means comprise a multiplicity of flashlamps.

21. The machine of claim 10 in which said light channels are fixed with respect to said arcuate projection zone, and said illuminating means is adapted to transmit light simultaneously through two adjacent light channels in order to properly illuminate a selected character when said character overlaps said discrete positions within the arcuate projection zone, the discrete positions being formed by light emanating from said two adjacent light channels at the time of projection of the selected character.

22. The machine of claim 1 in which:

said optical projection system includes a point size changing mechanism, and

said control means include circuit means for centering the line to be composed on the axis of said optical projection system by delaying the projection of the first character of the line to be composed by a time interval which is dependent upon the selected point size of said point size changing mechanism.

23. The machine of claim 1 in which:

said character-carrier includes a plurality of character type 60 styles,

said control means includes means to shift from one of said type styles to another, and

means are adapted to variably displace said image-receiving surface in conjunction with a style shift in order to compensate for relative displacement which occurs between said image-receiving surface and characters which are being projected when a shift in style occurs, so that the characters of a given line to be composed are projected along a common baseline of said image-receiving surface.

24. The machine of claim 1 in which:

said character-carrier includes a plurality of character type 70 styles,

said control means includes means to shift from one of said type styles to another,

said optical projection system includes means for changing the point size of said characters, and means are adapted to variably displace said image-receiving surface in conjunction with a style shift or point size change, in order to compensate for any relative displacement which may occur between said image-receiving surface and characters which are being projected when a shift in style occurs, when the point size is changed, or when a style shift and point size change occur simultaneously, so that the characters of a given line to be composed are projected along a common baseline of said image-receiving surface.

25. The machine of claim 24 in which:

said character-carrier has coaxially arranged rings of character type styles which pass simultaneously through said projection zone, and said variable displacement means includes a leading mechanism for moving said image-receiving surface, said leading mechanism comprising separate fine and coarse stepping motors for driving a differential system, the output drive of said differential system being adapted to move said image-receiving surface by relatively small increments.

26. The machine of claim 1 in which:

said illuminating means is positioned externally of said character-carrier, said arcuate projection zone is formed by a portion of the curved surface of said character-carrier, and master character images are projected radially inwardly of the projection zone onto means for reflecting the images along a common baseline of said image-receiving surface.

27. The machine of claim 26 in which said rotating character-carrier comprises a cylindrical drum, said image-receiving surface is a film, and said optical means for projecting said arcuate zone comprises a field-flattening lens.

28. A photographic type-composing machine comprising: a rotatable character-carrier having a curved surface bearing master characters to be projected, a surface for receiving projected images of said master characters such that lines of composition may be composed on said image-receiving surface, a projection zone of sufficiently large dimensions to include at least any one of said master characters at any given time as said characters pass through said projection zone, an optical projection system for projecting an image of the projection zone to said image-receiving surface, means for illuminating any one of said master characters while said character is in the projection zone, and

control means to vary the time at which said illuminating means is energized such that a selected character may be illuminated at any given time as it passes through said projection zone, said control means including: means for storing a complete line of characters to be composed, prior to projecting the first character of said line, and

means for sorting each of the characters of said stored line in accordance with its respective location on said character-carrier relative to a predetermined reference point, and the accumulated widths of the preceding characters in the line to be composed, such that said characters may be illuminated in a sequence which is dissimilar to their position in the composed line.

29. The machine of claim 28 in which said projection zone is arcuate, and the control means operates such that a full line may be composed during each revolution of said character-carrier.

30. The machine of claim 29 in which:

said arcuate projection zone is of sufficiently large dimensions to include at least two master characters at any given time as said characters pass through said projection zone, and

said optical projection means includes optical means adapted to project the arcuate projection zone as if it were flat, so that an undistorted image of said zone may be produced on the image-receiving surface.

31. The machine of claim 30 wherein said rotating character-carrier consists of a cylindrical drum, said image-receiving surface is a film, and

said optical means for projecting said arcuate zone comprises a field-flattening lens.

10

32. A photographic type-composing machine comprising: a continuously moving character-carrier bearing master characters to be projected, a surface for receiving projected images of said master characters such that lines of composition may be composed on said image-receiving surface, 15 a projection zone of sufficiently large dimensions to include at least any one of said master characters at any given time as said characters pass through said projection zone, an optical projection system for projecting an image of the 20 projection zone to said image-receiving surface, means for illuminating any one of said master characters while said character is in the projection zone, said illuminating means having associated therewith means for directing light emanating from said illumination means to 25

a plurality of discrete positions within said projection zone,

said light-directing means comprising a plurality of light channels, each of said light channels having a first end adjacent to said illuminating means for receiving light emanating therefrom, and a second end in close association with said projection zone for directing light emerging from each of said light channels to a discrete position within said zone, and

control means to vary the time at which said illuminating means is energized such that a selected character may be illuminated at any given time as it passes through said projection zone, said control means including:

means for storing a complete line of characters to be composed, prior to projecting the first character of said line, and

means for sorting each of the characters of said stored line in accordance with its respective location on said character-carrier relative to a predetermined reference point, and the accumulated widths of the preceding characters in the line to be composed, such that said characters may be illuminated in a sequence which is dissimilar to their position in the composed line.
